UNITED STATES PATENT OFFICE.

ANDREW LEYDEN, OF CHICAGO, ILLINOIS.

ASH-TRAY.

1,356,638.

Specification of Letters Patent. Patented Oct. 26, 1920.

Application filed June 5, 1919. Serial No. 301,937.

To all whom it may concern:

Be it known that I, ANDREW LEYDEN, a citizen of the United States, and a resident of the city of Chicago, county of Cook, and 5 State of Illinois, have invented certain new and useful Improvements in Ash-Trays, of which the following is a specification.

My invention relates to improvements in ash trays and has for its object the provision of an improved construction of this character, which is simple and efficient in operation and capable of folding into compact space.

Other objects will appear hereinafter.

15 The invention consists in the combinations and arrangements of parts hereinafter described and claimed.

The invention will be best understood by reference to the accompanying drawings 20 forming a part of this specification, and in which,

Figure 1 is a perspective view of an ash tray embodying the invention,

Fig. 2, a top plan view of said ash tray 25 shown in folded condition,

Fig. 3, a side view corresponding with Fig. 2, and

Fig. 4, a front view corresponding with Fig. 2.

30 The preferred form of construction as illustrated in the drawings comprises a body 5, preferably made of sheet metal, or the like, and having a plurality of grooves 6 extending transversely across said body from the front to the rear edge thereof and each 35 adapted to receive a cigar, or the like. Each of the grooves 6 is provided with a finger opening 7 properly distanced from the front edge of the body and adapted to facilitate the removal of cigars from said grooves.

An ash trough 8 is hinged at 9 to the front edge of the body 5 and is adapted to fold on to the top of said body as indicated. A trough 9 is provided at one end with a hinged door 9' to facilitate emptying the ashes therefrom, and the inner wall of said trough is provided with serrations 10 adapted to fit under the grooves in body 5, as shown. A supporting apron 11 is arranged 50 at the rear edge of the body being hinged thereto at the points 12, and is provided with a depending lip 11' adapted to close the inner ends of the grooves 6 when said apron is extended upwardly. The apron 11 is also 55 provided with two keyhole slots 13 adapted

to fit over nails or other headed studs on a wall, or the like, to serve as a convenient means for supporting the ash tray, when desired. Body 5 is also provided at its lateral edges with supporting legs or standard 14, 60 hinged at 15, to fold inwardly against the bottom of said body, and a match box support 16 is hinged at 17 to one side of said body. A stop lip 16' is provided at the corresponding edge of said body to limit the 65 outward swing of said match box support, as shown.

By this arrangement the ash tray, when extended, may be readily supported against a wall or other vertical surface or placed 70 upon a table, or the like. When out of use, the same may be folded into compact form, as indicated in Figs. 2, 3 and 4.

While I have illustrated and described the preferred form of construction for carrying 75 my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters 85 Patent is:

1. A device of the class described, comprising a body having a groove therein adapted to receive a cigar; a trough hinged at one edge of said body; and a supporting 90 apron hinged at the other edge of said body, substantially as described.

2. A device of the class described, comprising a body having a plurality of grooves extending transversely across the same, there 95 being an opening in each of said grooves situated at a distance from one edge of said body; an ash trough hinged to said one edge of said body, said ash trough having its inner side serrated to fit the grooves in said body; and a supporting apron hinged to the other edge of said body, said apron being adapted to close the corresponding ends of said grooves and being provided with key-hole slots for suspending the same, substantially 100 as described.

3. A device of the class described, comprising a body having a plurality of grooves extending transversely across the same, there 110 being an opening in each of said grooves

situated at a distance from one edge of said body; an ash trough hinged to said one edge of said body, said ash trough having its inner side serrated to fit the grooves in said body; a supporting apron hinged to the other edge of said body, said apron being adapted to close the corresponding ends of said grooves and being provided with key-hole slots for suspending the same; foldable legs for supporting said body; and a fold-

able match box supported at one edge of said body, substantially as described.

In testimony whereof I have signed my name to this specification in the presence of two subscribing witnesses.

ANDREW LEYDEN.
